CALENDER MACHINE

Charles P. Putnam, Lock Haven, Pa., assignor to
New York and Pennsylvania Co., Inc., New
York, N. Y., a corporation of Delaware

Application December 20, 1948, Serial No. 66,302

5 Claims. (Cl. 92—71)

1

This invention relates to calender machines for treating a web material such as paper and the like.

Specifically, this invention relates to a tandem-type supercalender machine which successively treats opposite faces of a web against hard surfaced rolls and includes swingably mounted resilient soft fiber or "paper" rolls which can be replaced without necessitating stoppage or slowdown of the calender machine.

This application is a continuation-in-part of my copending application Serial No. 626,477, filed November 3, 1945, now Patent Number 2,565,520.

Prior known supercalender machines either have a vertical stack of alternate hard surfaced rolls and soft surfaced "paper" rolls receiving the web in a serpentine path through the successive nips thereof or have a series of identical pairs of rolls in tandem relation successively receiving the web through the nips thereof as in my parent case Serial No. 626,477. In either type of these machines the web always has the same face pressed against the same type of roll viz either a hard roll or a soft roll.

Therefore, formation of a supercalender glaze on both faces of the paper has heretofore required the use of at least two machines.

The present invention now provides a supercalender machine which treats both faces of a paper web without lapping the web around the calender rolls.

A feature of the present invention is that successive calender rolls may be driven at any desired relative speed, thereby effectively compensating against any changes of length of the web as it is calendered.

Another feature is the provision of swingable "paper" rolls arranged to travel around different types of backing up rolls at successive nips in the machine.

A construction embodying the features of the present invention has additional advantages in that the web material may be successively passed through the nips of successive pairs of calender rolls arranged as desired thereby permitting the one face of the web to be in contact with hard rolls through one or more nips while the opposite face is in contact with the soft rolls and then reversing the procedure to contact this opposite face with the hard rolls while the first face contacts the soft rolls.

Inasmuch as damaged soft rolls can be replaced without stopping the calender machine, this invention makes it feasible to install supercalenders at the end of a paper making machine for continual assembly line operation and pro-

2

duction of calendered paper, thereby eliminating the cumbersome steps of loading and unloading supercalenders with heavy paper rolls.

The present invention further provides a supercalender whereby a hard metal roller is adjustably and compressibly urged against the top surface of a web material riding on a soft roll. Furthermore, such a supercalender is provided with an arrangement whereby the active soft roll and the spare soft roll may be rotated about a bottom driven roll through a 90° arc segment after which the previous active roll may be quickly removed on the operating floor of the machine room, thereby eliminating the necessity of loading and unloading soft rolls in a sub-basement beneath the supercalender machine as distinguished from those machines where removable soft rolls are rotated through 180°.

The supercalender machine of this invention includes a plurality of lower rigid driver rolls in spaced parallel relation. Each one of these rolls is driven by a prime mover such as an electric motor, or by any other driver arrangement which permits selective control of driver speeds.

The present embodiment, by way of preferred example only, has a pressure roll in spaced superimposed relation to each of the lower driver rolls. A first pair of soft paper rolls are swingably mounted for 180° rotation about the periphery of one pressure roll for selective pressure nip engagement with the bottom driver roll. A second pair of soft paper rolls are swingably mounted for 90° rotation about the periphery of a second lower driver roll in an adjacent roll assembly for selective pressure nip engagement with the corresponding pressure roll.

The superimposed pressure rolls are subjected to variable pressure in accordance with the desired nip pressure to be obtained between each paper roll and its corresponding cooperating hard metal roll. The lower rolls are driven at speeds which maintain the desired tension on the web material, thereby compensating against any discrepancies caused by successive stretching of the web material.

It is then an object of this invention to provide a calender machine of the character described in the foregoing.

Another object of this invention is to provide a calender machine adopted to continuously treat paper from a paper machine even when calender rolls are being changed.

A further object of this invention is to provide a roll arrangement for active and spare soft paper rolls of a calender machine which permits

rapid and convenient replacement of soft rolls with a rotating spare roll driven at a correct speed for engaging a traveling web passing through the calender machine.

A further object of this invention is to provide a calender machine which permits soft paper rolls to be removed on the operating floor level of the calender machine room.

A specific object of this invention is to provide a calender machine having a lower rigid roll, a pressure roll in spaced relation therefrom, and a plurality of soft calender rolls swingable about the periphery of the lower rigid roll to be selectively positioned in pressure nip relation with the pressure roll.

A further object of the invention is to provide a supercalender having a plurality of nips wherein in hard calender rolls may selectively contact both faces of the paper web being treated.

Other and further objects of this invention will be apparent to those skilled in the art from the following detailed description and the accompanying drawings which, by way of a preferred example only, illustrate one embodiment of the invention.

On the drawings:

Figure 1 is a side elevational view of a supercalender machine according to this invention with parts omitted and with connecting parts for the omitted parts shown in vertical cross section.

Figure 2 is an enlarged fragmentary view similar to Figure 1 but illustrating parts omitted from Figure 1.

Figure 3 is an enlarged broken transverse cross sectional view, with parts in end elevation and with parts broken away, taken substantially along the lines III-III of Figure 2.

As shown on the drawings:

A calender machine indicated generally at 10 includes a frame composed of pairs of front and rear upright columns 11 mounted on a machine room floor indicated generally at F and front and rear top beams 12 supported by the columns for supporting a number of supercalender roll mechanisms. The present embodiment shows a calender machine having two units, 10A and 10B, but it should be understood that the principles of the present invention are equally applicable to any structural combination of multiple calender roll mechanism units.

The calender roll mechanism 10A is similar to the calender roll mechanisms specifically described and claimed in the acknowledged parent application. As shown on Figure 1, the mechanism 10A comprises a lower driver roll 13 supported by a pair of bearing housings 14 secured to the floor F and arranged between a pair of the columns 11. The roll 13 may be driven by an independent variably controlled prime mover (not shown).

A pressure roll 15 supported in bearing housings carried by a pair of pressure roll supporting arms is positioned in spaced alignment above the lower drive roll 13. The pressure roll supporting structure and the pressure applying apparatus associated with the pressure roll 15 is identical with that to be described in appropriate detail in connection with the calender mechanism 10B in a subsequent portion of this disclosure.

A pair of soft or "paper" calender rolls 16 are rotatably mounted on diametrically opposed sides of the pressure roll 15 in peripheral engagement therewith. The soft rolls 16 may be rotated through 180° about the periphery of the pres-

sure roll 15 for selective pressure nip engagement with the lower roll 13. For a complete understanding and a detailed description of the mechanical means for accomplishing this rotation, reference may be had to the acknowledged parent application.

Referring now to Figures 1 and 2, the columns 11 of both the front and rear calender machine frames have vertical tracks or ways 11a along the inside length thereof facing the calender roll mechanism for slidably supporting movable carriages 18, to each of which a pressure roll supporting arm 19 is pivotally mounted.

A plurality of rods 20 depend through bosses on the top beams 12 in front of the carriages 18 for threaded engagement therewith via a plurality of cooperating spaced adjusting nuts 21, thereby permitting selective vertical adjustment of the levels of the carriages 18 relative to the top beams 12.

The pressure roll supporting arms 19 provide a pair of housings 22 for bearing structures which rotatably support the axle of a pressure roll 23 mounted between the pressure roll supporting arms 19.

Pressure may be selectively applied to the calender machine 10B or 10A, as for example, by applying controlled quantities of vertically directed force to the pressure roll 23 or 15. It should be understood, of course, that this application of pressure may be accomplished in various ways and with the aid of structures incorporating sundry mechanical designs. By way of illustration, but not by way of limitation, each calender roll mechanism of the present embodiment is shown as including a pressure apparatus comprising a pair of pressure applying arms 24 pivotally secured to corresponding carriages 18. The free ends of the arms 24 are respectively coupled to a threaded rod 26 which, in turn, depends from a worm and gear casing 27 (Figure 1) pivoted to a bracket 28 on the top of the beams 12.

A coiled spring or other resilient pressure device 29 is positioned between the roll carrying arm 19 and the corresponding pressure applying arm 24 so that downward pressure exerted upon the arm 24 by motor means M through the worms and gears (not shown) in the casing 27 and the rod 26 compresses the springs 29, thereby loading the pressure roll 23.

As shown on Figures 1 and 2, a pair of links 30 tie the free ends of the arms 24 to the respective ends of the arms 19 so that the rod 26 may be rotated to raise the pressure applying arm 24, the pressure roll carrying arm 19 and the pressure roll 23 as a unit. However, the links 30 have a lost motion connection comprising slots 30a for receiving a pin 19a formed on the free end of each arm 19, thereby permitting a linkage coupling without interfering with the resilient coaction of the pressure applying apparatus and the pressure roll 23.

Referring specifically to the calender roll mechanism 10B shown on the right hand side of the calender machine 10, a roll supporting frame 31 is mounted between the columns 11 and on the floor F (Figures 1 and 2). The frame 31 supports a bearing housing 32 which rotatably carries a lower driver roll 33 having very hard, preferably chilled iron, material on its peripheral surface.

As may best be seen on Figure 3, the roll 33 may be driven by a shaft 34 extending outwardly from said calender machine for connection to an

independent variably controlled prime mover such as an electric motor or the like (not shown).

As may best be seen by the dotted line outline shown on Figures 1 and 2 and by the full line view shown on Figure 3, the bearing housing portions 32 each have a cylindrical flange portion 32a surrounding an axle of the lower driver roll 33 and rotatably supporting a surrounding bracket 36. The bracket 36 is a bifurcated structure and has two pairs of outwardly projecting portions 36a spaced in radial alignment upon radially extending axes separated by an arc of 90°, which carry split bearing clamps 37 upon the outer free ends thereof. Each bearing clamp 37 includes pivoted-together clamping jaws adapted to be tightly clamped around an inserted bearing by means of clamping nut and bolt assemblies as shown.

The split bearing clamps 37 are arranged so that the pressure roll 23 can operate without interference from the bracket 36. Thus, the clamps float on the brackets 36 and are each comprised of a lower clamp arm 37a and an upper clamp arm 37b, the free ends of which are pivotally joined with one another by a pin 38 which, in turn, is carried by a boss 39 on a rod 40 pivotally mounted upon the bracket 36 as at 41.

The lower clamp arm 37a is pivotally secured to the projecting portion 36a of the bracket 36 as at 36c and the upper clamp arm 37b can be drawn up in bearing assembly by turning a nut 42 to engage a pointed washer 43 surrounding a swing bolt 44 pivotally mounted on an ear 36b extending from the projecting portion 36a of the bracket 36.

A pair of soft calender rolls 46, sometimes referred to as paper rolls because they are usually made of a metal core surrounded on their peripheries with compressed fiber or paper, are provided with laterally projecting axles 46a having bearings 47 mounted on the end thereof. The bearings 47 are adapted to be seated in the split bearing clamp 37 and are held therein against axial and rotational movement relative to the calender structure but permit free rotation of the soft rolls 46 within the bearing mounts.

As shown on Figures 1, 2 and 3, a pair of soft rolls 46 may be rotatably mounted in radial spaced alignment about the periphery of the drive roll 33. In the present drawings the upper soft roll is "active" and the roll displaced 90° to the right of the "active" roll is a "spare." Inasmuch as the lower driver roll 33 and soft rolls 46 are in peripheral engagement with one another, the peripheral speed of the spare roll is exactly the same as the linear speed of a web of paper W or the like shown traveling through the supercalender 10.

Thus, the rolls 46 removably retained by the bearing clamps 37 may be selectively positioned between the pressure roll 23 and the lower driver roll 33 by rotating the brackets 36 through a 90° arc around the circular flange 32a of the bearing housing 32. It will be apparent that a damaged soft roll 46 may be replaced in this manner without stopping the calender or slowing down the adjacent calender mechanisms since the spare soft roll eases into position at the correct rotary speed relative to the web material.

To accomplish this adjustment mechanically, the calender machine is equipped with a special mechanism. As may be seen on Figures 2 and 3, this mechanism includes a pair of ring gears 48 which are bolted to each of the brackets 36 in

surrounding relationship with the bearing flange 32a. The gears 48 mesh with a pair of smaller diameter gears 49 best seen on the right hand side of Figure 3 (where one of the gears 48 is cut away) mounted on a coaxial shaft 50 having fixed on the ends thereof a third pair of gears 51 of larger diameter than the gears 49. The gears 51 mesh with a fourth pair of gears 52 mounted in spaced relationship on a long shaft 53 extending transversely across the width of the calender mechanism.

The shaft 53 has affixed to the end thereof a smaller driven gear 54 in meshed engagement with a driver gear 56 connected to a prime mover P such as an electric motor or the like mounted on a bracket 57 extending from the frame 31.

The prime mover P is preferably an electric motor having field windings suitable for two directional operations and equipped with suitable limit switches and electric brakes. Thus, the motor P may be selectively energized to rotate the bracket 36 through a 90° arc by means of the gear train associated therewith to the dotted line position D indicated on the right hand side of Figure 1 or, from the dotted line position D to the full line position as shown.

Such selective operation will swing a spare calender roll 46 around the lower drive roll 33 into the space between the driver roll and the pressure roll 23. A split bearing clamp 37 may be quickly opened by manipulation of the swing bolt assembly and the previously active roll 46, now lying adjacent the lower drive roll as shown in Figure 1, can be conveniently and rapidly removed and replaced with a new soft roll, thereby effectively anticipating a future occasion for replacement of a soft roll.

It should be apparent that a calender roll mechanism thus equipped permits a web W to be introduced with the wire side of the web in contact with the soft roll 46 instead of the felt side being in contact with the soft roll. The present structure, therefore, permits alternate nip engagement with selected sides of a web W in a supercalender machine, as may be desired when it is necessary to calender both sides of a web material.

It should be further apparent that the novel structure permitting the changeover of spare and active soft rolls as herein described allows the removal of damaged soft rolls on the machine room floor level of the supercalender. Because of the size of supercalender machines, rotation of paper rolls about the lower drive roll 46 cannot be accomplished through 180° without necessitating removal of the damaged paper roll on a lower level or basement beneath the supercalender machine. The present invention, therefore, permits one level operation of supercalendering machines.

Whenever it is desired to adjust the pressure in the calender roll mechanism, the rods 26 are actuated downwardly, thereby exerting a vertical pressure force against the pressure arms 24 from whence the force is imparted to the pressure roll 23.

In operation, the lower driver roll 33 engages the interposed soft roll 46 which in turn, engages the pressure roll 23 limiting downward movement thereof. Pressure of the springs 29 is transferred to the pressure arms 24, roll 23 and lower driver roll 33, thereby causing the lower driver roll 33 to back up the active soft roll 46 along its entire length to create an even nip pressure be-

tween the pressure roll 23 and the active soft roll 46.

As best shown in Figure 1 a guide roll 57 is mounted adjacent the lower roll 13 and a paper web W passes under the guide roll and thence over the top portion of the lower roll 13. Such guide rolls thus cause the paper web W to partially lap around the lower rolls 13 and travel on these rolls through the nip of each supercalender assembly. The guide rolls 57 are preferably housed to receive heating or cooling fluid therethrough for adjusting the temperature of the web W before it passes through the succeeding nip. Thus, if desired, coolant can be flowed through the hollow guide rolls 57 to cool the paper or other web material and thereby aid in maintaining a cool nip temperature. Conversely, steam or other heating fluid can be flowed through the hollow guide rolls 57 to heat the web before passing through the nip.

Shower pipes S may be extended transversely across the top and bottom faces of the web W in spaced relation therefrom, and may be arranged to eject jets of steam, water or the like for treating the web before it passes through the nips of the supercalender. In many instances it is desirable to moisten the web so that a wet surface will be acted on by the nip of the supercalender.

The web W can be received into the first supercalender 10A directly from the dryer section of a paper machine and will pass under the first guide roll 57 and then through the first nip provided by the first supercalender assembly. It should be apparent that as a web is normally introduced into a calender machine, the active soft roll 16 is in contact with the felt side of the web W and the lower drive roll 13 is in contact with the wire side of the web W. The web will then pass under a second guide roll 58 from whence it will be introduced into the nip of a succeeding supercalender assembly.

As shown in this embodiment, the succeeding supercalender assembly is arranged in the manner of the calender mechanism 10B. Thus the web passes over the guide roll 59 and then passes over the lower portion of the pressure roll 23. It will be apparent that in this phase of the calendering operation, the one face side of the web W which had previously contacted the soft roll 16 in the first nip will now be contacted by the hard metallic surface of the pressure roll 23. Thus the soft roll 46 contacts the other side of the web W and the lower drive roll 33 serves as a backing roll. The web W, now calendered on both sides, passes over the guide roll 60 en route to a reel or winding apparatus. It may, of course, also be desirable to pass the web W through successive alternate nip engagement with additional supercalender assemblies.

Any stretching of the web W due to the pressure nip treatment in the various stages of the supercalender machine is accommodated by driving the successive drive roll faster to maintain any desired draw tension on the web. A supercalender machine constructed in accordance with the present invention can handle continuously moving web material directly from a paper machine to continuously supply a reel or winder with finished paper. The supercalender machine of this invention can also be used as finishing room equipment and may receive web material from a wound roll instead of directly from a paper machine.

It will, of course, be understood that various details of construction may be varied through

a wide range without departing from the principles of this invention and it is, therefore, not the purpose to limit the patent granted hereon otherwise than necessitated by the scope of the appended claims and the prior art.

I claim as my invention:

1. A calender machine comprising, in combination, a plurality of lower driver rolls having hard peripheries, said driver rolls arranged in spaced side-by-side relation, a frame having upright columns adjacent each of said driver rolls, a plurality of pressure applying rolls having hard metallic peripheries, said pressure rolls being superimposed above said lower driver rolls and between said columns, movable carriages mounted on said columns, pressure roll carrying arms pivotally connected to said carriages, said pressure roll carrying arms having bearing housings for rotatably carrying said pressure rolls, means connected to said frame for selectively applying variable quantities of vertical pressure force to said pressure rolls through said pressure roll carrying arms, a first pair of soft calender rolls rotatably mounted on diametrically opposed sides of one of said pressure rolls for 180° rotation about said pressure roll for selective first pass pressure nip engagement with a corresponding first pass lower driver roll, and a second pair of soft calender rolls rotatably mounted on radial axes respectively separated by a 90° arc for shifting around the upper portion of a second of said lower driver rolls for selective second pass pressure nip engagement with a corresponding second stage pressure roll.
2. A calender machine comprising a first roll, fixed bearings rotatably supporting said first roll, a pressure roll, bearings rotatably supporting said pressure roll, shiftable housings carrying said bearings, cylindrical flanges on said fixed bearings, brackets rotatably mounted on said flanges, a plurality of split bearing clamps carried by each bracket, a plurality of calender rollers having bearings removably clamped in said split bearing clamps, yieldable means accommodating swinging movement of the split bearing clamps relative to said brackets, means for rotating said brackets on the cylindrical flanges on said fixed bearings to selectively position the rollers into nip defining relation with the pressure roll, and pressure means for loading the bearings for the pressure applying roll to urge said pressure applying roll toward said first roll and thereby maintain a roller in pressure nip relation with the pressure applying roll.
3. A supercalender machine comprising tandem vertical stacks of rolls, each stack having top and bottom hard surfaced rolls in spaced superimposed relationship, a multi-roll carrier swingable about the periphery of the top roll in the first stack and including two spaced bracket members journaled for movement about the axis of rotation of the top roll of said stack of rolls, a second multi-roll carrier swingable about the upper portion of the bottom roll of the second stack of rolls including two spaced bracket members journaled for rotation about the axis of the next succeeding bottom roll, releasable clamping means movably mounted on each bracket member for rotatably supporting a pair of paper rolls, for movement with respect to said bracket members, to selectively position one paper roll between an associated stack of hard surfaced rolls and move the other paper roll in a position for easy replacement, said clamping means on said first mentioned bracket members being in

diametrically opposed relationship, and said clamping means on said second mentioned bracket members being spaced less than 180° apart, and means for guiding a paper web between the bottom hard surfaced roll and paper roll of one stack and thence between the top hard surfaced roll and paper roll of the next stack, to successively calender opposite faces of the web.

4. In a calendering machine for calendering a web material, a plurality of hard surfaced lower driver rolls and a plurality of vertically spaced hard surfaced upper pressure rolls longitudinally and horizontally aligned in tandem arrangement, spaced bracket members journaled for rotation about the axis of the first of said upper pressure rolls and bearing supports mounted on said brackets for limited movement with respect thereto, a first pair of soft calender rolls journaled in said bearing supports and swingably mounted to rotate about the first of said upper pressure rolls for selective nip engagement with a corresponding first of said lower driver rolls, spaced brackets journaled for rotation about the axis of the second of said lower driver rolls, bearing support means mounted on said brackets for limited movement with respect thereto and disposed in circumferentially spaced relation of less than 180°, a second pair of soft calender rolls journaled in said bearing supports and swingably mounted to rotate about the second of said lower driver rolls for selective nip engagement with the second of said upper pressure rolls, and guide rolls positioned adjacent said driver and pressure rolls, to partially lap the paper web over the first of said lower driver rolls for calendering one face of said web and then to direct the web onto the second of said pressure rolls, for calendering the other face of said web.

5. A calender machine comprising a plurality of rolls arranged in spaced tandem relation, a frame therefor including a plurality of spaced vertical columns, carriages mounted on said columns for adjustable movement therealong, means on said frame for raising and lowering said carriages along said columns, roll carrying arms pivoted on said carriages, pressure rolls rotatably carried by said roll carrying arms,

pressure applying arms pivoted on said carriages above said roll carrying arms, compression springs between the pressure applying arms and the roll carrying arms, links connecting the pressure applying arms and the roll carrying arms and accommodating limited vertical movements between the arms, means on said frame for swinging the pressure applying arms to load said springs and to raise the links for raising the roll carrying arms, brackets rotatable about the axis of one of said tandem rolls, a plurality of calender rolls rotatably mounted in said brackets and including an active calender roll in pressure nip relation with an adjacent lower roll and a spare calender roll on an adjacent side of the tandem roll, and means for shifting said brackets to move the spare calender roll into operative position with said adjacent pressure roll.
